(57) **CLAIM**

The ornamental design for a band, as shown and described.

DESCRIPTION

FIG. 1 is a front view of a first portion of a band, showing our new design.

FIG. 2 is a back view of FIG. 1.

FIG. 3 is a side view of FIG. 1.

FIG. 4 is an opposite side view of FIG. 1.

FIG. 5 is a top view of FIG. 1.

FIG. 6 is a bottom view of FIG. 1.

FIG. 7 is a front isometric view of FIG. 1.

FIG. 8 is a back isometric view of FIG. 1.

FIG. 9 is a front view of a second portion of the band, showing our new design.

FIG. 10 is a back view of FIG. 9.

FIG. 11 is a side view of FIG. 9.

FIG. 12 is an opposite side view of FIG. 9.

FIG. 13 is a top view of FIG. 9.

FIG. 14 is a bottom view of FIG. 9.

FIG. 15 is a front isometric view of FIG. 9;

FIG. 16 is a back isometric view of FIG. 9; and,

FIG. 17 is a perspective view thereof, showing the first and second portions of the band assembled in an environment of use.

The broken lines in the drawings illustrate portions of the band that form no part of the claimed design. The dot dash line illustrate unclaimed boundaries and form no part of the claimed design.

1 Claim, 5 Drawing Sheets
